(57) **CLAIM**

The ornamental design for a mirror, as shown and described.

DESCRIPTION

FIG. 1 is a first perspective view of a mirror showing my
new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the mirror
thereof.

The broken lines shown in the drawings depict portions of
the mirror that form no part of the claimed design. The
dash-dot-dash broken line illustrates the boundary of the
claim and forms no part of the claimed design.

1 Claim, 9 Drawing Sheets
